UNITED STATES PATENT OFFICE.

GEORGE W. GILMOUR, OF NEVADA, ASSIGNOR, BY MESNE ASSIGNMENTS, TO
JOSEPH W. BRANCH, OF ST. LOUIS, MISSOURI.

POST-HOLE AUGER.

SPECIFICATION forming part of Letters Patent No. 308,354, dated November 25, 1884.

Application filed March 19, 1884. (No model.)

To all whom it may concern:

Be it known that I, GEORGE W. GILMOUR, of Nevada, Vernon county, Missouri, have made a new and useful Improvement in Post-
5 Hole Augers, of which the following is a full, clear, and exact description, reference being had to the annexed drawings, making part of this specification, in which—

Figure 1 is a side elevation of the improved 10 auger; Fig. 2, a view in perspective of the bit; Fig. 3, a view in perspective of the lower end of the stock, and Fig. 4 a view in perspective of that part of the device employed in steady-
ing and feeding the auger.

15 The same letters of reference denote the same parts.

This improvement relates to the construction of the "blade" or "bit," as it may indifferently be termed, so as to increase its 20 spring or elasticity and reduce the liability of fracture; to the construction of the means for steady-
ing and feeding the auger, whereby the same shall serve to secure the bit to the stock, thus reducing the number of parts and sim-
25 plifying the construction of the auger without decreasing its efficiency, all as hereinafter described, and pointed out in the claims.

A represents the stock of the auger. At its upper end it is shaped to form or is provided 30 with a handle, and to this end it preferably is provided with the tubular cross-head, a, through which a handle (not shown) may be inserted. At its lower end the stock is shaped to receive the bit B, and so that the bit can be 35 readily attached to and detached from the stock, and when attached be prevented from turning around upon the stock. To this end the stock is provided with a shoulder, which is preferably in the form of the square projec-
40 tion a', Fig. 3, and above the projection, at a², the stock is larger in diameter than the projection a', to enable the stock to have a bearing upon the upper side of the bit. Below the projection a' the stock is extended to form 45 or is provided with the threaded end a³. The bit B for lifting and removing the earth is a thin plate of metal, preferably circular in form. At its center it has an opening, b, correspond-
50 ing to and adapted to fit the projection a' upon the stock. The bit is formed by means of a slit, b', which extends from the pe-

riphery of the blades inwardly toward the opening b, and at its inner end branches to form the slits b² b². By preference the slit b² is concentric with the stock, and terminates at 55 the ends in circular holes b⁴. By so constructing the disk the width of the cutting-blade is uniform, and its elasticity or spring is increased in the line of the applied power, so that there is less danger of fracture when stones or other 60 obstructions are struck. Moreover, by curving the slits b² and causing them to terminate in the holes b⁴ any tendency of transverse or extended cracking of the bit is avoided. The bit is completed by sharpening the edges 65 b³ b³ of the slit b', so as to form cutting-edges, and bending the plate, so as to bring the edges b³ b³ out of line with each other and out of and respectively above and beneath the plane of the remainder of the plate, 70 and substantially as shown in Figs. 1, 2. This not only forms a bit, but a reversible one, for the bit can be used either side up, and according as the bit is attached the lower edge, b³, for the time being is the cutting-edge, and 75 the other of the edges b³ b³ is meanwhile being sharpened. The blade is attached to the stock by passing the projection a' into the opening b, and then screwing a nut onto the threaded end a³ of the stock, and so as to secure the bit 80 upon the projection a' and against the shoulder a². This nut, however, is made to serve another purpose—to feed the auger, and also, preferably, to steady it. To this end the nut C is provided with the spiral points c c, which 85 enter and loosen the ground in advance of the bit, and thereby facilitate the action of the bit. The points curve in the same direction as the edges b³ b³, respectively, and the threads upon the end a³ and nut run in such direction 90 that in operating the auger the tendency is to tighten the nut. To steady the auger, the nut is furnished with the center point, c', which projects downward between the points c c.

I do not herein, broadly, claim a reversible 95 bit for earth-augers, as the same has been formed heretofore by combining two semicircular disks; but

I claim—

1. A blade or cutter for earth-augers, con- 100 sisting of a single disk of plate metal having a radial slit bifurcated at its inner end, the

edges of the radial slit being turned out of line to form the cutters, substantially as and for the purposes specified.

2. A bit or blade for earth-augers, having a slit concentric with the stock-socket and a radial slit extending from the concentric slit to the periphery of the disk, the edges of the radial slit being turned out of line to form the cutters, substantially as and for the purposes specified.

3. A bit for earth-augers, having a slit concentric with the stock-socket, which slit terminates in holes or perforations, and a radial slit which extends from the concentric slit to the periphery of the disk, substantially as and for the purposes specified.

4. In an earth-auger, the combination, with a stock, of a blade or cutter consisting of a plate-metal disk having a radial slot which forms the cutting-tongues, and a nut for se-

curing the blade to the stock, said nut having the spiral feeders, substantially as and for the purposes specified.

5. The combination, in an earth-auger, of a stock, a detachable and reversible disk-bit, and the nut having the centering-point and spiral feeders, substantially as and for the purposes specified.

6. The earth-auger shaft having the angular seat and threaded end, in combination with the bit having an angular opening and the feeder having the threaded center, substantially as and for the purposes specified.

In testimony whereof I have affixed my signature, in presence of two witnesses, this 3d day of March, 1884.

GEORGE W. GILMOUR.

Witnesses:

PAUL BAKEWELL,
M. T. JANUARY.
